UNITED STATES PATENT OFFICE.

ANDERS G. ANDERSON, OF LOS ANGELES, CALIFORNIA.

FIREPLACE-HEATER.

1,287,815.

Specification of Letters Patent. Patented Dec. 17, 1918.

Application filed March 14, 1918. Serial No. 222,462.

To all whom it may concern:

Be it known that I, ANDERS G. ANDERSON, a citizen of the United States, residing at Los Angeles, in the county of Los Angeles and State of California, have invented new and useful Improvements in Fireplace-Heaters, of which the following is a specification.

My object is to make a fire place heater having a radiator through which the products of combustion circulate and around which fresh air circulates, so as to heat the fresh air and discharge it into the room, and my invention consists in the novel features herein shown, described and claimed.

Figure 1 is a front elevation of a fire place provided with a heater embodying the principles of my invention and taken looking in the direction indicated by the arrows 1 in

Figs. 2 and 3.

Fig. 2 is a side elevation of that part of the fire place which projects into the room, as seen looking in the direction indicated by the arrows 2 in Figs. 1 and 3.

Fig. 3 is a horizontal section on the line 3—3 of Fig. 1.

Fig. 4 is a staggered sectional front elevation substantially on the line 4—4 of Fig. 3.

Fig. 5 is a vertical cross-section on the line 5—5 of Fig. 4.

Fig. 6 is a fragmentary vertical cross-section on the line 6—6 of Fig. 4.

The mantel 1 is built in front of the wall and has a chimney 2 and a fire place 3. A grate 4 is mounted in the fire place 3 some distance above the floor 5, and an ash chamber 6 is constructed below the grate, there being a door 7 in the back wall of the ash chamber so that when the door is opened the ashes and cinders may be discharged down the chute 8 into the lower part of the chimney. A draft regulator 9 is constructed in the front wall of the ash chamber and a slatted screen 10 extends upwardly from the forward side of the grate 4. Solid walls 11 and 12 are built of fire brick or the like, from the floor up, at the ends of the ash chamber 6 and grate 4. A back fire wall 13 extends upwardly between the walls 11 and 12 and from the back side of the grate 4 to a considerable height, and a return wall 14 extends from the upper edge of the wall 13 downwardly and backwardly, there being an air space 15 between the walls 13 and

14 for circulation of air to keep the walls from burning, said walls being preferably constructed of heavy sheet iron. An air chamber 16 is formed below the ash chamber 6 and air chambers 17 and 18 are formed between the walls 11 and 12 and the side walls 19 and 20 of the mantel, there being a grille 21 covering the entrance to the air chamber 16 and grilles 22 and 23 covering the entrances to the air chambers 17 and 18, so that fresh air may pass inwardly through said grilles 21, 22 and 23. A baffle wall 24 extends downwardly from the top 25 of the fire place 3 back of the return wall 14, there being a passage 26 between the return wall 14 and the baffle wall 24, said passage leading downwardly and discharging into the lower end of the radiator 27. A flue 28 leads from the top of the fire place 3 to the chimney opening 29, there being a damper 30 at the lower end of said flue controlled by a rod 31 connected to the damper and extending through the front wall 32 of the mantel, there being a handle 33 upon the forward end of the rod in front of the mantel for operating the damper, so that when the damper 30 is opened the products of combustion from fuel burning upon the grate 4 will pass straight up through the fire place and through the flue 28 and so that when the damper 30 is closed the products of combustion must pass downwardly through the passage 26 to the radiator 27.

The details of the radiator construction 27 are as follows: The radiator is built of sheet iron and comprises means forming a heat passage 34 into which the passage 26 discharges, heat passages 35 and 36 leading upwardly from the ends of the passage 34, a heat passage 37 leading horizontally from the passage 35, a heat passage 38 extending upwardly from the other end of the passage 37, a heat passage 39 extending horizontally from the heat passage 38, a heat passage 40 extending horizontally from the upper end of the passage 36, a heat passage 41 extending upwardly from the other end of the passage 39, a heat passage 42 extending upwardly from the other end of the passage 40, a heat passage 43 extending horizontally from the passage 41, a heat passage 44 extending horizontally from the passage 42, a heat passage 45 extending upwardly from the other end of the passage 43, a heat passage 46 extending upwardly from the other

end of the passage 44, a heat passage 47 extending horizontally from the passage 46, and outlets 48 and 49 leading from the passages 47 and 45 to the chimney opening 29.

5 The sheet iron boxes forming the heat passages are mounted between upright metal bars 50 and 51, said bars being connected by bolts 52, 53, 54 and 55, certain ones of the boxes resting upon the bolts and the bolts 10 serving to clamp the bars against the front and back sides of the boxes. In setting up the boxes forming the heat passages they are spaced apart to form fresh air passages 56, 57, 58, 59, 60 and 61 extending forwardly 15 and backwardly between the boxes, and the radiator thus constructed is set in the chimney back of the fire place and back of the baffle plate 24 so as to form fresh air passages 62 and 63 at the back and front of the 20 radiator and communicating with the passages 56-61 through the radiator, there being a fresh air chamber 64 below the radiator to which the chambers 16, 17 and 18 lead. Passages 65 lead from the top of the 25 radiator upwardly and forwardly through the mantel and discharge through the grille 66 in the front face and upper part of the mantel 1. In plan, the boxes forming the radiator 27 comprise straight central portions 67 and forwardly inclined end portions 68 and 69.

Correspondingly inclined clean-out openings 70 and 71 are formed through the side walls 19 and 20 of the mantel.

35 Openings 72 and 73 are formed in the ends of the boxes of the radiator. Covers 74 and 75 are adapted to close the openings 72 and 73 and panels 76 and 77 are adapted to close the openings 70 and 71, so that when it 40 is desired to clean out the heat passages in the radiator the panels 76 and 77 may be removed and the covers 74 and 75 removed and instruments inserted to clean the heat passages.

45 In the practical operation, a fire is built upon the grate 4, the damper 30 is opened until the fire is well started, then the damper 30 is closed and the products of combustion will pass downwardly through the passage 50 26 to the passage 34 and pass upwardly from both ends of the passage 34 and then zig-zag upwardly through succeeding passages to the outlets 48 and 49 and to the chimney opening 29. Fresh air will be drawn into the chamber 64 through the grilles 21, 22 and 23 and pass upwardly into the air space 55 15 where it will be highly heated between the back 13 and the return back 14, and this

fresh air will pass upwardly from the chamber 64 around the radiator and the hot air 60 will pass outwardly through the grille 66 into the room. In this manner a large amount of the heat from the products of combustion will be extracted by the radiator and communicated to the fresh air and discharged into the room.

Various changes may be made in the details of construction without departing from the spirit of my invention as claimed.

I claim:

1. A fire place heater comprising a grate, a back wall extending upwardly from the grate, a return wall extending downwardly from the upper edge of the back wall; there being a fresh air space between the two walls, an ash chamber below the grate, means forming a fresh air passage below the ash chamber and behind the walls, a radiator mounted in the fresh air passage and consisting of horizontal boxes spaced apart and 75 forming back and forth passages for the products of combustion and having clean-out openings in their ends, said clean-out openings being accessible through openings in the sides of the mantel, and means for conducting the products of combustion from above the grate through the radiator.

2. In a fire place heater, a mantel and chimney having a fire place chamber, a grate in the forward part of the chamber, a wall 90 extending upwardly from the back of the grate and downwardly, a baffle wall extending downwardly back of the first walls and forming a down passage, a radiator mounted in the back part of the chamber and consisting of horizontal boxes spaced apart 95 forming back and forth passages leading to the chimney and having clean-out openings in their ends, said clean-out openings being accessible through openings in the sides of the mantel, and means for passing fresh air upwardly around the radiator and out at the top of the mantel.

3. In a fire place heater, a mantel and chimney having a fire place chamber, means 105 forming a fire box in the front part of the chamber, and means forming a radiator in the back part of the chamber; said radiator consisting of horizontal boxes spaced apart and connected together and having clean-out openings in their ends; said clean-out openings being accessible through openings in the sides of the mantel.

In testimony whereof I have signed my name to this specification.

ANDERS G. ANDERSON.
